ELECTRICAL APPARATUS COMPRISING A
WIRING CAST BY EXTRUSION

Eduard Maria Henricus Lips, Eindhoven, Netherlands, assignor to Hartford National Bank and Trust Company, Hartford, Conn., as trustee

Application May 2, 1947, Serial No. 745,476
In the Netherlands June 13, 1946

3 Claims. (Cl. 173—324)

1

The invention relates to electrical apparatus, for example, radio-receiving apparatus, provided with a wiring formed, by means of an extrusion process, as one unit, on an insulating supporting plate to which it is secured. Component parts are mounted on this support by passing the ends of supply conductors which form part of these components through apertures provided in the insulating support, the ends protruding from these apertures being embedded in the material of the wiring. An apparatus of this type is known from French additional specification 50,893 to French specification 838,738.

In casting such a wiring difficulties are encountered due to the fact that, under the influence of the very high moulding pressure of several tens of atmospheres, the liquid casting material penetrates through the apertures along the supply wires of the components which pass through the apertures of the support, often damages the components and, after solidification, forms projections the removal of which results in supplementary costs and loss of time.

It might be endeavoured to avoid these difficulties by ensuring an exact fit of the supply conductors in the apertures provided in the support, in which event the difference in diameter must be about 0.06 mm. at the most. In this case, however, it is very difficult to introduce the supply conductors into the apertures, since these wires, due also to the tin coating, are never perfectly straight and smooth and, generally, cannot be introduced into the apertures exactly in the direction of the axis of the bore, so that they often get jammed in these apertures, which again results in loss of time and costs. A favourable compromise between these costs and those which are due to the penetration of the casting liquid through the apertures cannot be found either.

According to the invention, these difficulties are obviated by providing at least one insulating intermediate plate of materially less thickness than the support between the latter and the wiring, at least one supply conductor integral with a component being passed through an aperture in the intermediate plate, which aperture fits without clearance around the supply conductor and registers with an aperture of the support. A, for example circular, intermediate plate may be provided under each aperture of the support, although preferably use is made of a single intermediate plate which covers the whole of the support. Since the intermediate plate is much thinner than the support, the possibility of the supply wires getting jammed is greatly reduced and,

2

if this should occur, it will be readily possible to force the wires through the apertures in the materially thinner wall. It is even very well possible to utilize an intermediate plate of such small thickness that there is no need at all of providing beforehand apertures in it and to pierce the supply wires of the components through this thin plate, a highly satisfactory closure of the apertures by the supply conductors being thus naturally ensured.

The invention will now be described in connection with the drawing in which:

Fig. 1 shows a top view of the wiring arrangement;

Fig. 2 is a sectional view along the line II—II of Fig. 1; and

Fig. 3 shows sectional view of a wiring arrangement wherein the component parts are arranged on opposite sides of the supporting base.

An insulating supporting plate 1, for example, of moulding material or of hard paper, with a thickness of about 1 mm., exhibits two apertures 3 and 5, through which wire-shaped supply conductors 7 and 9 of a component, in the present case a condenser 11, are passed. In contact with the bottom-surface of the support 1 is provided an insulating intermediate plate 13, for example of hard paper, in which apertures 15 and 17 are provided which register with the apertures 3 and 5. The wires 7 and 9 also pass through the apertures 15 and 17 in which they fit without any clearance. This may be achieved by forcing the wires through the plate 13, which may have a thickness of from 0.05 to 0.04 mm. and which, beforehand, is not provided with apertures.

The assembly formed by the two plates 1 and 13 is located in between the parts of a mould 19 and 21. The top matrix 19 is provided with an aperture 23 (cf. Fig. 1) to allow the passage of the component 11. It is thus made possible to mount this component on the support prior to the introduction of the support 1 into the mould, so that during the mounting the mould is not occupied.

The matrix 21 exhibits channel-like recesses 25 and 27 which may be brought into communication with a vessel containing molten moulding material and which, in the casting process, are filled with liquid metal. The wiring thus formed may be secured to the support by means of simultaneously cast rivets (not shown) in the manner as described in French Patent 838,738. As may be seen from Fig. 2, the metal embraces the ends of the supply wires 7 and 9 passing through the plates 1 and 13, a conductive con-

nection being thus established. The intermediate plate 13 prevents the casting liquid from penetrating through the apertures 3 and 5 under the influence of the high moulding pressure and from damaging the condenser 11 or from forming spurs which have to be removed afterwards, which removal involves a great risk of damaging the wires 7 and 8.

Owing to the presence of the intermediate plate 13, the diameters of the apertures 3 and 5 may be from 1 to 2 mms. larger than those of the supply wires, so that the wires can be passed through without the least difficulty. It is, however, also advantageous to make the difference in diameter smaller, for example 0.2 mm., it being thus ensured that the supply wires, which are, in this case, slightly jammed in the apertures, assist in securing the wiring (25, 27) to the support.

In Fig. 3, the component parts 11 and 16 are mounted on opposite sides of support 1 provided with apertures for passing terminal leads of the component parts through the support. On both sides of the support are plates of insulating material 13 and 14 provided with apertures for passing the terminal leads through without clearance. The ends of the terminal leads are embedded in extruded die-cast conductors 22, 24, 25 and 27, respectively, forming the wiring connections for the component parts.

What I claim is:

1. A wiring system for component parts of electrical apparatus having terminal leads for establishing electrical connections thereto comprising a plate-shaped insulating supporting base with suitably spaced apertures therein for passing the terminal leads of said component parts therethrough with clearance, a plurality of extruded wire conductors having enlarged terminal portions die-cast on one side of said supporting base, and an intermediate plate-shaped insulating member having a thickness which is substantially less than one-half the thickness of said base between said wire conductors and said supporting base in the region of each of said apertures, said intermediate member having apertures aligned with the apertures in said supporting base for passing said terminal leads therethrough without clearance to prevent penetration of the wire-conductor material during the die-casting process, said terminal leads being embedded in the terminal portions of said extruded conductors to establish electrical connections thereto.

2. A wiring system for component parts of electrical apparatus having terminal leads for establishing electrical connections thereto comprising

a plate-shaped insulating supporting base with suitably spaced apertures therein for passing the terminal leads of said component parts therethrough with clearance, a plurality of extruded wire conductors having enlarged terminal portions die-cast on opposite sides of said supporting base, and an insulating plate having a thickness which is substantially less than one-half the thickness of said base between said wire conductors and said supporting base, said intermediate plate having apertures aligned with the apertures in said supporting base for passing said terminal leads therethrough without clearance to prevent penetration of the wire conductor material during the die-casting process, said terminal leads being embedded in the terminal portions of said extruded conductors to establish electrical connections therewith.

3. A wiring system for component parts of electrical apparatus having terminal leads for establishing electrical connections thereto comprising a plate-shaped insulating supporting base with suitable spaced apertures therein for passing the terminal leads of said component parts therethrough with clearance, a plurality of extruded wire conductors having enlarged terminal portions die-cast on both sides of said supporting base, and an intermediate plate-shaped insulating member having a thickness which is substantially less than one-half the thickness of said base between said wire conductors and said supporting base in the region of each of said apertures, said intermediate member having apertures aligned with the apertures in said supporting base for passing said terminal leads therethrough without clearance to prevent penetration of the wire-conductor material during the die-casting process, said terminal leads being embedded in the terminal portions of said extruded conductors to establish electrical connections thereto.
